DESIGN FOR A BANNER OR SIMILAR ARTICLE OF MANUFACTURE

Murray Hedley Stone, New York, N. Y.

Application May 5, 1943, Serial No. 110,118

Term of patent 14 years

To all whom it may concern:

Be it known that I, Murray Hedley Stone, a citizen of the United States and resident of New York, county of Queens, and State of New York, have invented a new, original, and ornamental Design for a Banner or Similar Article of Manufacture, of which the following is a specification, reference being had to the accompanying drawing, forming a part thereof, and which is a face view of a banner embodying my design.

I claim:

The ornamental design for a banner or similar article of manufacture, as shown.

M. HEDLEY STONE.
